L. L. KENYON.

COOPERATING MEANS FOR BANJO HEADS.

APPLICATION FILED MAY 28, 1920.

1,349,067.

Patented Aug. 10, 1920.

UNITED STATES PATENT OFFICE.

LOUIS L. KENYON, OF IOWA CITY, IOWA.

COÖPERATING MEANS FOR BANJO-HEADS.

1,349,067.

Specification of Letters Patent. Patented Aug. 10, 1920.

Application filed May 28, 1920. Serial No. 384,994.

To all whom it may concern:

Be it known that I, LOUIS L. KENYON, a citizen of the United States, residing at Iowa City, in the county of Johnson and 5 State of Iowa, have invented certain new and useful Improvements in Coöperating Means for Banjo-Heads; and I do hereby declare the following to be a full, clear, and exact description of the invention, such 10 as will enable others skilled in the art to which it appertains to make and use the same.

This invention embodies attachments for and the manner of applying the same to the 15 heads of that type of stringed musical instruments broadly which employ a parchment or gut cover stretched over an otherwise open rim support for enhancing the sound vibrations of its associated attuned 20 strings.

As the invention has been primarily devised, however, more especially with relation to improvements in coöperating means 25 for banjo heads, for the sake of brevity I shall only illustrate and describe the same with reference to that specific instrument.

The invention may be said to broadly reside in the particular appliance itself as well as in the special manner of its attachment, whereby it dually functions both as to 30 providing means for the delicate tautening of the parchment cover to the desired pitch and more particularly the distribution of the vibratory motions to the woody parts 35 of the instrument in conjunction with the more freely vibratory parchment, thereby toning off the sounds emitted to relieve them materially of the "thumpy" like twanging common to the banjo; but as these and 40 other objects and advantages will be so clearly apparent, as incidental to the following disclosures, it would perhaps be only undesirable surplusage to further refer to the same initially, and with these prefacing 45 remarks, therefore, reference will be immediately had to the accompanying drawings, illustrating a practical embodiment of the improvements, in which drawings

Figure 1 is an inverted perspective view 50 of the head of a banjo with the invention applied thereto; Fig. 2 is a longitudinal sectional view with the head reversed and the section being taken along the line 2—2 of Fig. 1; Fig. 3 is a cross-sectional view taken 55 in the plane of the line 3—3 of Fig. 2; and Figs. 4 and 5 are detached perspective views

of the two adjustably coacting elements of the improved attachment.

5 designates the annular rim support of the banjo head, which is usually formed of 60 metal, 6 is its fretted neck of seasoned wood, and 7 is a seasoned wooden strut bar forming a continuation of the neck, within the rim, and providing a reinforcing intermediate element. 8 designates the parchment 65 cover or head which is stretched over the head rim, its securing and ordinary tautening means being indicated conventionally by the wedging hoop or band 10 in association with its engaging peripheral series of 70 threaded adjusting rods 9, while 11 simply designates the bridge of the banjo and 12 the strings thereof, all of these features being old and well understood.

Referring now to the structural formation 75 of my own improvements, 15 indicates one element of the attachment which has a straight flat base face 16, with a transversely disposed slot 17 opening to the opposite face and the side faces of the member, 80 which slot is slightly deeper at one end than at the other, thus providing an inclined plane surfaced bottom therefor.

The other element of the attachment is an elongated member of uniform thickness 85 to snugly slide in said slot, the body of this member being indicated at 18 and having the beveled or tapering edge face 19, an opposite straight edge face 20, and the smaller and larger ends 21 and 22, respectively. 90

It would seem to be desirable, from my experiments so far, that these two members should be formed of wood, although other kinds of suitable material might later be 95 found to satisfactorily answer the purpose, and when they are fitted together it is to be observed that the inclined edge face 19 of the wedge piece is disposed downwardly in the slot 17 to slidingly bear against the 100 inclined face of the latter, with the large end 22 of the wedge piece projecting from that end of the slot that is the deepest, so that the straight edge face 20 of the wedge piece will be constantly parallel to the plane 105 of the face 16 of the slotted member.

In carrying out my invention in its entirety the slotted member 15 is so positioned on the strut bar 7, with the flat base 16 of the former seating upon the upper 110 face of the latter, that when the wedge piece is inserted in the slot, and forced

home, its straight edge face 20 will snugly engage the underneath face of the parchment head 8 at a position substantially distant from the position of the bridge member 11 resting upon the upper face of the parchment head. Furthermore, the members should be so disposed that the large end 22 of the wedge piece will be in the uppermost position, when the instrument is being played upon, in order to more positively insure the elements being held intact against displacement from any vibratory causes.

In actual practice, I find that the best results appear to be attained when the wedge piece is disposed at a position approximately three-eighths of an inch to the rear of the bridge piece, and from there on in a lesser degree as the attachment is moved farther rearwardly when the tones again begin to resolve themselves into those of the regularly played banjo with the ordinary "thumpy" twanging.

It seems that at this particular position, of three-eighths of an inch behind the bridge, although the particular position may vary slightly with different sized heads, a clearer, purer and sweeter musical resonance results.

It is my understanding that this is caused by the vibrations being so distributed, by way of the improved bridging-over appliance interposed between the parchment head and the strut bar, that they are proportionately divided between both the neck and the head, instead of the parchment head alone vibrating as heretofore, whereby there results a more harmoniously sweet woody tone in conjunction with the banjo effect proper, excepting that the "thumpy" discordant sounds of the latter are entirely eliminated. In other words, by this arrangement it would appear that sufficient vibratory motion is provided for the parchment head itself, to retain the regular banjo tones minus the "thumping," whereas enough wood vibration is also brought into action, through the interposed parts and neck, to combine proportionately with the other and thus producing the more desirable dulcet tones sought for. At any event, whether or not I have exactly stated the proper reasons therefor, experimental use has assuredly demonstrated to me at least that my discovery is of superior importance in point of preserving the purity of tone values.

Another important advantage of this arrangement is that it enables the performer to play with a pick or plectrum much more effectively, no doubt due to the more or less restricted vibration of the parchment head *per se*, it being observed that somewhat of a dampering effect is imposed thereon by placing the supporting wedge piece at a

position outside of the plane of the bridge piece 11, without actually muffling or muting the resonant characteristics of the parchment head for proper tone enhancement.

A still further important advantage of my improvements is that, owing to the adjustable wedging action of the member 18, the tautness of the parchment or gut head membrane may be so regulated to a nicety that the instrument may be properly attuned even with a moderately tight head, whereas otherwise the instrument's parchment has to be strained almost to the breaking point in order to get the best results. In consequence, the life of a banjo head, provided with my attachment, would be indefinitely prolonged, in comparison with the ordinary banjo heads, on account of the lessening of strains thereon.

Having thus made a full disclosure of my invention as at present practised, and while the improved attachment is simplicity itself, nevertheless it will be understood that I do not wish to unnecessarily restrict myself to the exact details as shown and described, excepting as limitations may be imposed by the terms and scope of the ensuing claims, when fairly interpreted in the light of the specification and understood equivalents.

What I do claim, as new and patentable, is:—

1. The combination with a banjo, or analogous musical instrument embodying a rim support, a parchment head therefor, a neck, a strut bar within said rim and providing a continuation of said neck, and a string bridge seated on said head; of a wedge member having an inclined underneath edge face and a straight upper edge face transversely interposed between said head and said strut bar, with its straight edge face directly engaging the underneath face of said head and its inclined edge face adjustably supported by said strut bar, substantially as described.

2. The combination with a banjo, or analogous musical instrument embodying a rim support, a parchment head therefor, a neck, a strut bar within said rim and providing a continuation of said neck, and a string bridge seated on said head; of a wedge member having an inclined underneath edge face and a straight upper edge face transversely interposed between said head and said strut bar at a position substantially distant from the position of said bridge element, the said wedge member having its straight edge face directly engaging the underneath face of said head and its inclined edge face adjustably supported by said strut bar, substantially as described.

3. The combination with a banjo, or analogous musical instrument embodying a rim support, a parchment head therefor, a neck, a strut bar within said rim and providing a

continuation of said neck, and a string bridge seated on said head; of a wedge member having an inclined underneath edge face and a straight upper edge face transversely 5 interposed between said head and said strut bar substantially to the rear of said bridge element, the said wedge member having its straight edge face directly engaging the underneath face of said head with its inclined 10 edge face adjustably supported by said strut bar, substantially as described.

4. The combination with a banjo, or analogous musical instrument embodying a rim support, a parchment head therefor, a neck, 15 a strut bar within said rim and providing a continuation of said neck, and a string bridge seated on said head; of a base member supported by said strut bar and having a transverse open slot providing an inclined 20 bottom face; and a wedge member having a straight upper edge face and an inclined underneath edge face, the said pair of members being so adjustably associated and interposed between said head and said strut 25 bar that the straight edge face of the wedge piece transversely extends in direct engagement with the underneath face of said head while its inclined edge face is slidingly supported within said slot, substantially as 30 described.

5. The combination with a banjo, or analogous musical instrument embodying a rim support, a parchment head therefor, a neck, a strut bar within said rim and providing a 35 continuation of said neck, and a string bridge seated on said head; of a base mem-

ber supported by said strut bar and having a transverse open slot providing an inclined bottom face; and a wedge member having a straight upper edge face and an inclined 40 underneath edge face, the said pair of members being so adjustably associated and interposed between said head and said strut bar that the straight edge face of the wedge piece transversely extends in direct engagement with the underneath face of said head, at a position substantially distant from the position of said bridge element, while its inclined edge face is slidingly supported within said slot, substantially as described. 45

6. The combination with a banjo, or analogous musical instrument embodying a rim support, a parchment head therefor, a neck, a strut bar within said rim and providing a continuation of said neck, and a string 50 bridge seated on said head; of a base member supported by said strut bar and having a transverse open slot providing an inclined bottom face; and a wedge member having a straight edge upper face and an inclined 55 underneath edge face, the said pair of members being so adjustably associated and interposed between said head and said strut bar that the straight edge face of the wedge piece transversely extends in direct engagement with the underneath face of said head at a position substantially to the rear of said bridge element while its inclined edge face is slidingly supported within said slot, substantially as described. 60

In testimony whereof I affix my signature.
LOUIS L. KENYON.
